UNITED STATES PATENT OFFICE.

VERNON L. LEVINGSTON, OF LAKE CHARLES, LOUISIANA.

DRIVEN-HEADED FASTENING.

Application filed June 7, 1921. Serial No. 475,709.

To all whom it may concern:

Be it known that I, VERNON L. LEVINGSTON, a citizen of the United States, residing at Lake Charles, in the Parish of Calcasieu and State of Louisiana, have invented certain new and useful Improvements in Driven-Headed Fastenings, of which the following is a specification.

The invention relates to improvements in 10 nails or other forms of similar fastenings adapted to be driven to operative position.

The principal object of the invention is to provide for a fastening of the character described, and one embodying a locking 15 means effective, upon the final driving movements, to securely retain the fastening in its operative position against displacement through accident, or, for all practical purposes, against ordinary attempts for its 20 withdrawal or removal from locked position.

Another object of the invention is to provide for a driven fastening of the type mentioned, and one wherein the locking 25 means is integrally formed with the fastening, and is of a nature and arrangement whereby to not increase the present cost of manufacture of such devices to an appreciable amount.

30 With the foregoing and other objects in view, the invention resides in the certain novel and useful construction and arrangement as will be hereinafter more fully described, set forth in the appended claims, 35 and illustrated in the accompanying drawing, in which,

Figure 1 is an elevation of the preferred embodiment thereof,

Fig. 2 is a section taken on line 2—2 of 40 Fig. 1, and,

Fig. 3 is a similar view taken on the line 3—3 of Fig. 1.

Referring to the drawing, the numeral 10 indicates the body portion or shank of a 45 nail form of fastening; 11 the pointed end of the same, and 12 the driving head thereof. Formed radially of the body 10 at a slight distance inwardly from the lower pointed end 11, is a tapering lug or projection 13 which is circular in plan and having a squared upper end, forming the positive locking means of the device, and which is formed to provide a flat horizontally dis-

posed upper face, and a downwardly and inwardly inclined outer or lower face, the 55 latter face being provided to decrease the resistance of the lug or projection 13 to the driven movement of the body 10 into the work. Formed on the body 10, downwardly from a point immediately or slightly 60 below the driving head 12, is a spiral rib or screw thread 14, which is adapted to impart to the body 10 more than a half revolution, or less, of turning movement in the work, during the final driving of the device, 65 the lower end of the rib or thread 14 being preferably of a substantial knife edge formation whereby to facilitate the final driving movement of the body, and to further decrease the resistance offered to such 70 driving movement.

In the driving of the fastening thus provided, the lug or projection 13 enters the work during the initial driven movement of the body 10, and passes straight downward with the latter until the lower sharpened end 14', of the rib or thread 14, enters the work, when upon further driving movement to the body 10, a turning movement will be imparted to the same and will 80 continue for slightly more than a half revolution, during the final driving movement of the body, whereby the lug or projection 13 will move in a spiral path of a sharper pitch than that of the rib or thread 14, and until the device is fully driven home. When finally driven home in the work, the nail or other similar fastening will be securely held against any and all ordinary attempt for its 85 withdrawal and removal from position, and will otherwise effectively maintain its operative position throughout its period of continued use in the work.

It is well understood that the device may be made in any of the usual and ordinary 95 forms of driven headed fastenings without regard to size or configuration, other than as shown, without departing from the spirit of the invention or the scope of the claim appended hereto.

Having thus fully described the invention, what is claimed is:—

A driven headed fastening including a body portion, a work penetrating lug formed on the body portion and having a downwardly and inwardly inclined face for de-

creasing the resistance offered thereby to the driven movement of the body, said lug being circular in plan and having a squared upper end and a spiral rib formed on the 5 body above the extension for imparting a turning movement to the body portion and said extension during the driving opera-

tion, the inner end of said spiral rib being of a knife edge formation whereby to reduce the resistance thereof to the driven movements, as aforesaid. 10

In testimony whereof, I affix my signature hereto.

VERNON L. LEVINGSTON.
